UNITED STATES PATENT OFFICE

FREDERICK W. LINAKER AND THEODORE M. BEUBACK, OF DU BOIS, PENNSYLVANIA

TUBE CLEANER

Application filed April 12, 1923. Serial No. 631,644.

This invention relates to devices for cleaning the tubes of boilers, economizers and the like, commonly known as soot-cleaners, and aims to provide improvements therein.

5 The invention provides improvements in the type of soot cleaners where the valves are located close to the cleaner element, and both the valve and element are operated by a single operating means, as disclosed in the patent of Frederick W. Linaker No. 1,413,601, granted April 25, 1922, one of the present applicants. In the present improved construction, the opening and closing of the valve is automatically effected, through the operation of a single means which operates both the valve and the element, the entire structure being simple in construction, compact and reliable.

20 Several embodiments of the invention are illustrated in the accompanying drawings.

Referring to said drawings, and Figures 1 to 7, inclusive, are views of one embodiment, Figures 8 to 11 views of a second embodiment very similar to the first.

25 Figure 1 is a sectional view of the valved end of a cleaning element;

Figure 2 is a sectional view on the line II-II, in Figure 1;

30 Figure 3 is a view similar to Figure 2 showing the parts in a slightly different position;

Figure 4 is a sectional view on the line IV-IV, Figure 1;

Figure 5 is a detached view of the valve seat;

35 Figure 6 is a detached view of the valve disk;

Figure 7 is a detached view of the locking member or pawl;

40 Figure 8 is a view similar to Figure 1, the valve seat and disk being in the form of cones;

Figure 9 is a sectional view on the line IX-IX, Figure 8;

Figure 10 is a sectional view on the line X-X, Figure 8;

45 Figure 11 is a top plan view of one of the valve parts (62) shown in Figure 10, broken away at one end and detached from the other parts of the mechanism.

50 In each of the structures illustrated, the turning of the operating means serves to first

open the valve to admit steam to the cleaning or blowing element, and as its movement continues the element is turned from its initial position of rest through any desired arc to project jets of steam against the required range of tubes, during which movement the valve is held open; on the return movement the valve is again closed as the element is turned back to its position of rest.

Referring to Figs. 1 to 7 of said drawings:

Numeral 10 designates the cleaning element, which extends through a sleeve 12 in the wall 14 of a boiler setting, or the like, into, or adjacent to, a bank of tubes for cleaning the latter, by jets of steam, in well-known manner. An end of the cleaning element 10 also has a turning connection with a head 16, which receives steam from a branch pipe 18. The turning connection may be in the form of a gland 20, of usual construction.

The head 16 forms the casing of a valve 22, controlling the flow of steam to the element 10. The valve 22 conveniently comprises a seat member 24, which is fixed upon the element 10, as indicated at 25, and a disk or valve proper 27 turning on a pivot 28, conveniently formed as a projection from the valve seat member 24. The valve seat 24 and the disk 27 are provided with openings or ports 29, 30, adapted when in registry to admit steam to the element, and when out of registry, to stop the flow of steam into the element.

The element 10 is turned or oscillated by any suitable operating means 33 (to cause the jets from the element to sweep through the tube space) and these means 33 also serve as a part of the means whereby the valve 22 may be automatically opened and closed.

36 designates a lock or locking member or pawl having a recess 37 therein, adapted to coact with a lug or projection 38, the pawl 36 in this embodiment being pivotally mounted upon the disk 27, as indicated at 39, and the lug or projection 38 being upon the seat member 24.

The ports 29 and 30 are designed to be in registry when the lug 38 is in the recess 37 of the locking pawl 36. During the turning of the cleaning element, it is desired that the

100

valve remain open, that is, that the ports 29 and 30 remain in registry. Means 42 are therefore provided for preventing the disengagement of the lug 38 from the recess 37 of the locking pawl during that part of the turning movement corresponding to the cleaning action of the cleaning tube 10. In the present embodiment, this means 42 is conveniently a part of the inner wall of the head 16, which projects into close proximity to the pivoted locking member 36, preventing turning thereof, and thereby preventing the disengagement of the lug 38 from the recess 37 in said pawl.

At the point where it is desired to close the valve, the means 42 for preventing disengagement of the lug 38 from the locking pawl 36, is provided with a recess 43, or other suitable arrangement, which permits the pawl 36 to turn, and the lug 38 to thereby be moved out of engagement with said pawl. At the point where the valve is designed to be closed, means 47 are provided for preventing the further turning of the valve part on which the pivoted pawl 36 is mounted, this being shown as the valve disk 27. These means conveniently comprise a projection 48 on the valve casing, and a coacting projection 49 on the disk 27. The recess 43 and the stop or projection 48 are so related in position that when the projection 49 strikes the projection 48 (thereby stopping the further movement of the disk 27) the pawl 36 may move up into the recess 43, thereby permitting the lug 38 to move out of the recess 37 in the pawl 36 (see Fig. 2). Means are preferably provided for stopping the movement of the lug 38 after passing out of engagement with the pawl 36, in a position where the ports 30 therein are out of registry with the ports 29 of the valve disk. This means is conveniently a projection 50, carried by the same part which carries the lug or projection 49, being in this embodiment the valve disk 27, and when the lug 38 comes into contact with the said lug 50, movement of the seat member 24 on which the lug 38 is mounted, is prevented, and the valve parts 24 and 27 are stopped in position with the ports 29 and 30 thereof out of registry.

Means are also provided for preventing the lug 38 from moving out of engagement with the recess 37 of the locking pawl 36, after it has moved into engagement with said recess 37, and while the pawl 36 is still in position to be turned into said recess 43. This means is conveniently a lug or projection 53, on the valve part 27.

After the locking pawl 36 has passed beyond the recess 43, the lug 38 may be turned in either direction without the pawl 36 being able to turn to disengage said lug 38. Consequently, while the lug 38 is locked in the pawl 36, the ports 29 and 30 of the valve parts 24 and 27 are locked or held in open relation.

Operation.—When not in operation, the parts are in the positions shown in Fig. 2, the valve being closed. To open the valve the means 33 (here shown as a sprocket to be turned by a chain) is operated to turn the element 10 and seat member 24, thereby moving the lug 38 thereon from the position shown in Fig. 2 to that shown in Fig. 3. During the initial movement the valve member 27 is prevented from turning by the engagement of the pawl 36 in the recess 43 (as shown in Fig. 2); when the lug 38 enters the recess 37 in the pawl 36, its further movement turns the pawl to bring it out of the recess 43 (see Fig. 3); and by this movement of the seat member 24, while the valve member 27 remains stationary, the steam ports 30, 29, are brought into coincidence, thereby admitting steam into the element 10. At this time the lug 38 strikes the projection 53 on the valve part 27 and initiates the turning of the two valve parts 24 and 27 in unison. This movement continues during the entire rotation of the element 10, so as to project jets into the boiler tube space through a prescribed angular sweep, until the farthest point of rotary movement is reached, after which the element is turned in the contrary direction toward its starting point. On the return movement, when the lug 49 strikes the stop 48 on the valve casing, the lugs 48, 49, come into contact, so that further movement of the disk 27 is prevented. At this time (see Fig. 3), the pawl 36 is in position to turn into the recess 43. Continued movement of the element 10 will cause the lug 38 to turn the pawl 36 up into the recess 43, and the lug 38 will itself move out of the recess 37 in the pawl 36, the valve seat 24 thereby moving independently of the valve disk 27, and bringing the ports 30 therein out of registry with the ports 29 of the said valve disk 27, and thereby closing the valve. The valve part 24 is stopped in the closed position of the valve by the lug 38 thereon coming into contact with the projection 50 on the valve part 27, which is at this time held against movement by the contact of the lug 49 thereon with the projection 48 on the valve casing (see Fig. 2).

Second embodiment.—Referring to Figures 8 to 11 inclusive, the valve seat member is in the form of a cone 60, and the valve disk is in the form of a corresponding cone 62. The member 62 is formed with a recess 63, within which there is fitted a pawl 36'. The pawl 36' has a hooked end 64 which is movable through an opening 65 in the recessed part of the coned valve 62 into and out of engagement with a shoulder 66 in a recess 66' on the cap 67 in the position of said valve 62 and valve seat member 60 where the ports 29 and 30 are out of registry. The pawl has an arm 68 adapted to be struck by a projection 38' on the valve seat member 130

60 for turning the pawl 36' to carry the hooked portion 64 out of engagement with the shoulder 66, so that the valve 62 can be moved. When the projection 38' bears against the 5 arm 68 the recessed part 37' of said pawl is pressed and held against said projection 38', so that the hooked end 64 may be carried past the shoulder 66 and continues to turn with said projection 38' when turned clockwise. 10 Inclined faces 69 are provided between the projection 38' and the pawl 36', but the inner wall 70 of the cap 67 prevents the pawl 36' from turning on its pivot under the action of said inclined faces 69 when the projection 38' is turned counter-clockwise, and until the recess 66' is reached, whereupon the inclined faces 69 act to push the hooked end 64 of the pawl 36' into said recesses 66'. After the hooked end 64 is pushed into the recess 66' 20 the projection 38' may continue to move until it strikes a projection 71 on the inner side of said valve part 62. Simultaneously, the projection 49 on the valve part 62 comes against the projection 48 on the cap 67 and 25 further movement of the projection 38' in a counter-clockwise direction and of the valve part 60 on which it is mounted is stopped.

A pintle 72 on the valve seat member 60 serves as a trunnion in which said valve part 30 62 turns, and lock nuts 72 on the end of said pintle 72 serve to hold the said part 62 in place. A socket 73 in said cap 67 may also be provided, into which the end of said pintle 72 may project and thereby support the over-hand of the element 10 in the casing 16.

Operation.—The operating means 33 turns the element 10, carrying the valve seat member 60 thereon, as described with reference to Figures 1 to 7 inclusive. When the projection 38', carried by the valve part 60, is engaged in the recess 37' of the pawl 36' carried by the valve part 62, the ports 29 and 30 are in registry, and the element 10 may be turned in either direction, without closing the valve, 45 so long as the pawl 36' is kept away from the position of the recess 66'. When the valve is to be closed, the element 10 is turned so far that the lug 38' on the valve part 60 brings the pawl 36' to the position of the recess 66'. At this time the projection 49 on the valve part 62 comes against the fixed projection 48. The movement of the valve part 62 carrying the pawl 36' is thereupon stopped. Movement of the element 10 and valve part 60 thereon, produces relative movement between the valve parts 60 and 62, this being 50 permitted by the fact that the inclined faces 69 between the pawl 36' and projection 38' on the valve part 60 move the said hooked end 64 of the pawl 36' into the recess 66' and allows the said projection 38' to move out of the pawl recess 37' toward the shoulder 71. When the projection 38' on the valve part 60 55 strikes the shoulder 71 on the stopped valve part 62, the ports 29 and 30 are fully out of

registry, and the part 60 carrying the lug 38' is stopped in this position. The position of the parts at this time is shown in Figure 9.

To open the valve, the means 33 is operated to turn the element 10 in a clockwise direction, bringing the lug 38' into the recesses 37' in the pawl 36' and against the arm 68 thereby turning the hooked end 64 of the pawl out of the recess 66' and disengaging it from the shoulder 66, and when the lug 38' and recess 37' are fully engaged the ports 29 and 30 are 70 completely in registry, and the movement in unison of the valve parts 60 and 62 begins (Fig. 10). After the pawl moves away from the recess 66' the lug 38' is locked therein and the two valve parts 60, 62, may be moved in either direction without closing the valve, inasmuch as the turning of the pawl 36' is prevented by the inner wall 70 of the cap 67. While the valve part 60 is being 75 turned relatively to the valve part 62 (in the act of opening the valve) movement of the valve part 62 by the friction between said parts is prevented by the engagement of said hooked end 64 of the pawl 36' (on the part 62) with the shoulder 66 on the fixed valve cap 67.

The inventive ideas herein set forth may receive other embodiments than those herein specifically indicated and described.

In any of the embodiments set forth it is desirable that the element be rotated either continuously or intermittently, as may be desired. For continuous rotation the part 33 may be the usual sprocket wheel engaged by a chain. For intermittent rotation (which for many practical reasons is preferable) the part 33 may be a ratchet wheel moved in one direction or the other by a driving pawl, such, for example, as the mechanism set forth in our application filed April 12, 1921, Serial No. 460,661.

What is claimed is:

1. In combination, a rotary soot cleaner element, and a two-part valve for controlling the admission of steam thereto, one valve-part being fixed on said element, means for turning said element, said means also turning one of said valve-parts, and means operated by said turned-valve-part for connecting and disconnecting said valve-parts to one another, said valve-parts, when connected, moving together in open position, and, when disconnected, being relatively movable to open or closed position by the turning of said element-turning means.

2. In combination, a rotary soot cleaner element, and a two-part valve for controlling the admission of steam thereto, one valve-part being fixed on said element, means for turning said element, said means also turning one of said valve-parts, and means operated by said turned-valve-part for connecting and disconnecting said valve-parts to one another, said valve parts, when connected, mov-

ing together in open position, and, when disconnected, being relatively movable to open or closed position by the turning of said element-turning means, said connecting means comprising a pivoted locking member on one of said valve parts.

3. In combination, a rotary soot-cleaner element, and a two-part valve for controlling the admission of steam thereto, one valve-part being fixed on said element, means for turning said element, said means also turning one of said valve parts, and means operated by said turned-valve-part for connecting and disconnecting said valve-parts to one another, said valve-parts, when connected, moving together in open position, and, when disconnected, being relatively movable to open or closed position by the turning of said element-turning means, said connecting means comprising a pivoted locking member on one of said valve parts, and means for preventing the turning of said locking member during the time said element is moving through a prescribed range of oscillation.

4. In combination, a rotary soot cleaner element, and a two-part valve for controlling the admission of steam thereto, one valve-part being fixed on said element, means for turning said element, said means also turning one of said valve parts, and means operated by said turned-valve-part for connecting and disconnecting said valve-parts to one another, said valve-parts, when connected, moving together in open position, and, when disconnected, being relatively movable to open or closed position by the turning of said element-turning means, said connecting means comprising a pivoted locking member on one of said valve parts, means for preventing the turning of said locking member during the time said element is moving through a prescribed range of oscillation, and means allowing the turning of said locking member after said range is exceeded for permitting the valve-parts to be disengaged, whereby said turned valve part may move to close said valve at the desired position.

5. In combination, a rotary soot cleaner element, and a two-part valve for controlling the admission of steam thereto, one valve-part being fixed on said element, means for turning said element, said means also turning one of said valve parts, and means operated by said turned-valve-part for connecting and disconnecting said valve-parts to one another, said valve-parts, when connected, moving together in open position, and, when disconnected, being relatively movable to open or closed position by the turning of said element-turning means, said connecting means comprising a pivoted locking member on one of said valve-parts, and a stop for limiting the movement of the last mentioned valve-part.

6. In combination, a rotary soot cleaner

element, and a two-part valve for controlling the admission of steam thereto, one valve-part being fixed on said element, means for turning said element, said means also turning one of said valve parts, and means operated by said turned-valve-part for connecting and disconnecting said valve-parts to one another, said valve-parts, when connected, moving together in open position, and, when disconnected, being relatively movable to open or closed position by the turning of said element-turning means, said connecting means comprising a pivoted locking member on one of said valve parts, and a stop for limiting the movement of said turned-valve part after movement of said other valve-part has been stopped.

7. In combination, a rotary soot cleaner element, and a two-part valve for controlling the admission of steam thereto, one valve-part being fixed on said element, means for turning said element, said means also turning one of said valve parts, and means operated by said turned-valve-part for connecting and disconnecting said valve-parts to one another, said valve-parts, when connected, moving together in open position, and, when disconnected, being relatively movable to open or closed position by the turning of said element-turning means, said connecting means comprising a pivoted locking member on one of said valve-parts, and a stop for limiting the movement of the last mentioned valve-part, and means in conjunction with said stop allowing the turning of said locking member for permitting the valve parts to be disengaged, whereby said turned-valve-part may move to close said valve at the desired position.

8. In combination, a rotary soot cleaner element, and a two-part valve for controlling the admission of steam thereto, one valve-part being fixed on and turned with said element and the other valve-part being movable relative thereto, means for turning said element, and means operated by said turned-valve-part for connecting and disconnecting said valve-parts to one another, said valve-parts, when connected, moving together in open position, and when disconnected, being relatively movable to open or closed position by the turning of said element, said connecting means comprising a pivoted locking member on said other valve-part, and a stop for limiting the movement of the other valve-part, and means in conjunction with said stop allowing the turning of said locking member for permitting the valve parts to be disengaged, whereby said turned-valve-part may move to close said valve at the desired position, and a second stop for limiting the movement of said turned-valve-part after movement of the other valve-part has been stopped.

9. In combination, a rotary soot cleaner

element, and a two-part valve for controlling the admission of steam thereto, one valve-part being fixed on and turned with said element, means for turning said element, and means operated by said turned-valve-part for connecting and disconnecting said valve-parts to one another, said valve parts, when connected, moving together in open position, and, when disconnected, being relatively movable to open or closed position by the turning of said element, said valve parts comprising a seat member and a valve-member, said turning means being connected to said element, and said seat member being fixed on said element.

10. A rotary soot cleaner element according to claim 1, the means for connecting and disconnecting the valve parts being a lock, and internal cam surfaces for operating such lock.

11. In combination, a rotary soot cleaner element, and a two-part valve for controlling the admission of steam thereto, one valve-part being fixed on and turned with said element, means for turning said element, said means also turning one of said valve parts, and means operated by said turned-valve-part for connecting and disconnecting said valve-parts to one another, said valve-parts, when connected, moving together in open position, and, when disconnected, being relatively movable to open or closed position by the turning of said element-turning means, said valve parts being conical.

12. In a tube cleaner, a rotary blower element, a supply pipe, an intervening head forming a chamber, a valve within said chamber controlling flow from said pipe into the element, and operating means for turning the element and an operative connection for operating the valve, located wholly within said chamber and adapted to open the valve as the element is turned from its initial position of rest, and to close it on the reverse return movement, and to hold the valve open during the remaining rotation of the element.

13. In a tube cleaner, a rotary blower element, a supply pipe, an intervening head forming a chamber, a valve within said head controlling flow from said pipe into the element, operating means for turning the element and means wholly within said chamber for operating the valve, adapted to open the valve as the element is turned from its initial position of rest, including means for locking the valve in open position during the remaining rotation of the element, in said open position and adapted to close the valve on the return movement of the element.

14. In a tube cleaner, a rotary blower element, a supply pipe, an intervening head forming a chamber, a valve within said head controlling flow from said pipe into the ele-

ment, operating means for turning the element and for operating the valve, adapted to open the valve as the element is turned from its initial position of rest, and to close it on the reverse return movement, and a lock for holding the valve open, movable with the rotating element, and a stationary retaining member for engaging the lock to hold it in locking position, except in the initial position of rest of the element.

15. In a tube cleaner, a rotary blower element, a supply pipe, an intervening head forming a chamber, a valve within said head controlling flow from said pipe into the element, operating means for turning the element and for operating the valve, adapted to open the valve as the element is turned from its initial position of rest, and to close it on the reverse return movement and a lock for holding the valve open, movable with the rotating element, and a stationary retaining member for engaging the lock to hold it in locking position, said member having a recess coinciding with the normal initial position of the lock to permit the release of the lock and closing of the valve in said position.

In witness whereof, we have hereunto signed our names.

FREDERICK W. LINAKER.
THEODORE M. BRUBACK.
